UNITED STATES PATENT OFFICE

105,437

DESIGN FOR AN ICE CUBE CUTTER

William J. La Casse, Duluth, Minn., assignor to
The Coolerator Company, Duluth, Minn., a cor-
poration of Minnesota

Application May 17, 1937, Serial No. 69,389

Term of patent 7 years

To all whom it may concern:

Be it known that I, William J. La Casse, a citizen of the United States, residing at Duluth, in the county of Saint Louis and State of Minnesota, have invented a new, original, and ornamental Design for an Ice Cube Cutter, of which the following is a specification, reference being made to the accompanying drawing, forming a part thereof in which

Fig. 1 is a perspective view showing the top and two sides of my new design; and

Fig. 2 is another perspective view showing the bottom and two sides of my new design.

I claim:

The ornamental design for an ice cube cutter, as shown.

WILLIAM J. LA CASSE.
